UNITED STATES PATENT OFFICE.

CHARLES H. BROWN, OF BROOKLINE, MASSACHUSETTS, ASSIGNOR TO BERENICE BROWN, OF BROOKLINE, MASSACHUSETTS.

LAST.

1,237,464.

Specification of Letters Patent. Patented Aug. 21, 1917.

Application filed December 1, 1915. Serial No. 64,542.

To all whom it may concern:

Be it known that I, CHARLES H. BROWN, a citizen of the United States, and resident of Brookline, in the county of Norfolk and 5 State of Massachusetts, have invented an Improvement in Lasts, of which the following description, in connection with the accompanying drawing, is a specification, like characters on the drawing representing like 10 parts.

This invention relates to a novel construction of shoe lasts.

This last is of a configuration such that 15 shoes made thereon will have a construction adapted to correspond more closely to the anatomical structure of the human foot and will provide means for bracing those arched portions of the foot which naturally function to sustain the stress of the load carried.

20 The construction of the human foot is such that it has two members which are substantially bridge structures. The longitudinal foot arch is trussed by the bow-string which is attached to the heel bone and leads substantially 25 along the median portion of the foot bottom to the ball of the foot at which end it has several attachments at different points just back of the forward transverse arch, known as the anterior or metatarsal 30 arch. This transverse arch is formed by the joints of the ball of the foot. This arch rests upon a pad or cushion of flesh which in walking barefooted is pressed upon by the bones of this arch. The bone structure 35 is such that the tension of the weight borne thereon spreads these bones apart and, when the weight is lifted, they are immediately contracted by the flexible ligaments fastening the bones together. This action, resolved 40 into a cycle of operations in walking, functions as a pump for the blood to assure the proper circulation in the foot.

The present disadvantages and defects of 45 the last structure overcome in this novel structure are several. The shank of the present last structure is rounded and is also relatively too short as the shoes formed thereon have shanks which are not long enough with relation to the forepart and 50 heel properly to brace the bow-string. Round shank lasts produce a shank in a shoe which presents a concaved surface as a support for the bow-string which, as stated, is naturally formed to be presented to a flat 55 or approximately flat surface. And, being

relatively too short, the normal bow-string is without support at that portion of the present shoe which is just at the rear of the usual tread portion. This non-supported and non-fitted portion is comprehended between the points at which the bow-string is attached to the anterior arch and the junction of the usual shank and concaved inner-sole. Hence, the bow-string sags at this portion. Further, the usual rounded last 60 shank is not of a configuration destined to form a shoe shank which will fully and efficiently carry the bow-string portion as well as the curved inner portion of the instep of the foot. A serious defect of the last commonly employed is that the forepart is convexed or rounded, an especially disadvantageous factor at the tread portion of the forepart or ball. The shoes finished from such lasts have innersoles which present a con- 70 caved or rounded surface to the foot. Such conformation strains and tends to break down the flexible ligaments of the anterior arch, as the human foot is constructed to be placed upon a flat surface and not upon a 75 surface simulating the interior of a tube. Such a surface as is presented to the bottom of the foot by shoes formed on the usual lasts, also operates to curtail, if it does not ultimately prevent, the effectuation of the 80 blood pumping function of this flexible arch.

These disadvantages are overcome in this novel last structure by forming a last in which there is a radical departure from the present generally rounded shank portion. Herein, the shank portion is longer 90 with relation to the last forepart, the under surface of the forepart is substantially flat and a novel conformation is given to the portion of the forepart forwardly extending from the usual tread thereof so that the shoe formed on this last has a forward tread 95 extension.

An object of this invention is to provide a shoe last such that shoes made thereon will 100 correspond more closely to the formation of and more efficiently coöperate with the functions of the human foot.

A more specific object is to provide a shoe last having a relatively short forepart, 105 a tread extension and a novel shank portion.

Other objects of the invention will more fully appear from the following description and accompanying drawings and will be pointed out in the annexed claims. 110

In the drawings:

Figure 1 is a view in elevation of the novel last;

Fig. 2 is a plan view of the bottom of the last;

Fig. 3 is a section on the line 3—3 of Fig. 2, looking toward the forepart of the last.

In this selected embodiment of this invention disclosed in the accompanying drawings, there is illustrated a last of the two-part type though obviously lasts embodying this invention may be of any of the general types. The relatively long heel 1 has secured thereto, by any suitable means, the usual heel seat plate 2. The last shank or longitudinal bow-string arch 3 runs from the forward end of this heel seat to the forepart 4 of the last. The shank of the last, in relation to the forepart of the last, is longer than in the usual last conformation. The toe portion 5 of the forepart is slightly upwardly turned, as indicated in Fig. 1, while the tread portion 6, the middle transverse portion of the forepart, is substantially flat or substantially in the plane of the horizontal as shown in Fig. 1. An approximately concave surface 7 is formed in the under face of the last. This surface 7 meets the tread portion 6, as here shown, in the transversely arcuate line 8. Rearwardly, this surface, in this preferred embodiment, joins the inner surface 9 and the outer surface 10 of the under surface of the shank in the lines 11 and 12, which form a generally obtuse angle, the apex of which is at the forward termination of the line 13 formed by the intersection of the two shank-forming portions.

The shank, as noted, is substantially angular in cross-section. The outer surface 10 of the shank is longitudinally arcuate and is of such conformation that its transverse elements are all, in this preferred embodiment, substantially parallel to each other and also to the transverse elements of the flat tread portion 6 of the forepart.

This conformation corresponds generally to the foot bow-string structure and a shoe formed on this novel last will be provided with a relatively broad bow-string supporting surface. Further, in the formed shoe, this outer supporting portion 10 provides a transversely flat surface to be offered to the bow-string and thus properly functions to support this portion of a foot more efficiently than does the interiorly rounded or concaved shank of a shoe formed on the usual last having the rounded or completely curved shank contour.

In the selected embodiment illustrated, the shank inner surface 9 begins at a point well back of the forward end of the heel seat and runs to the concave surface 7 meeting it as indicated by the line 11. This inner surface 9 is also longitudinally arcuate in con-

formation. In the preferred form, the transverse elements of the inner surface 9, however, are curved. These elements, beginning at the line 13 which defines the inner side of the outer surface 10, are upwardly curved 70 and their continuations become the transverse elements of the inner side of the upper portion of the last. In other words, this transversely arcuate inner portion curves into the last upper. Those transverse elements of this inner shank surface 9 which are adjacent the concave surface 7 are slightly concaved which effectuates a relatively short extension of this concave surface 7 into the inner surface 9 of the last shank. 80

There is thus presented a novel last structure by means of which shoes formed thereon will more easily correspond to and more efficiently coöperate with the natural structure and functions of the human foot. 85

The relatively lengthened last shank results in a proportionately lengthened shank in the formed shoe, so that the long cord or bow-string is more completely supported throughout its length from the anterior arch 90 back to its junction with the heel bone. The formed shoe will also be provided with a tread extension which will substantially form an outside rearward continuation of the tread portion of the shoe and to a relatively slight degree the innersole will be convexed to afford greater support to the rear portion of the anterior or transverse ball arch. 95

Having fully described my invention, 100 what I claim as new and desire to secure by Letters Patent is:

1. A shoe last having fore, shank and heel parts, the under surface of the shank being formed by angularly apportioned inner and outer surfaces, the inner surface when continued meeting the outer surface in a line extending longitudinally of the shank, and forming an outwardly presented angle, the transverse elements of the outer surface being approximately horizontal. 110

2. A shoe last having fore, shank and heel parts, the under surface of the shank having defined inner and outer surfaces and the heel part having a heel seat, the inner portion only of the surface of the heel seat being shaped to form substantially a continuation of the shank inner surface in order to conform to the human foot structure. 115

3. A shoe last having fore, shank and heel parts, the under surface of the shank formed by angularly apportioned inner and outer surfaces and the fore part rearwardly extending and meeting said shank, the line of intersection of said surfaces forming a substantially obtuse angle. 120

4. A shoe last having fore, shank and heel parts, the tread portions of the fore part having its transverse elements substantially horizontal and having a substantially con- 130

caved rear portion whereby arch-supporting means are provided in a shoe formed upon said last.

5. A shoe last having a fore part and a shank, the under surface of the shank being formed by angularly apportioned inner and outer surfaces, the tread portion of the fore part being substantially flat and the outer of said angularly apportioned shank surfaces having its transverse elements substantially parallel to those of said tread portion.

10. A shoe last having a forepart and a shank, the under surface of the shank being formed of an inner and an outer surface, the tread portion of the forepart being substantially flat, the outer surface of the shank having its transverse elements substantially parallel to those of said tread portion and the inner surface of the shank having its transverse elements upwardly curved and extended to form the elements of the inner side of the upper portion of the last, said shank surfaces forming at their intersection

25 an outwardly presented angle.

7. A shoe last having a forepart, a shank and a heel, the under surface of the shank

being formed of an inner and an outer surface, said surfaces meeting in an outwardly presented angle, the inner portion of the 30 heel seat being shaped to form a substantial continuation of the inner surface of the shank, and the forepart having an angular portion rearwardly extending to the shank part, the construction and relation of the 35 parts being such that a shoe formed thereon offers means for supporting the several arches of the human foot.

8. A shoe last including a shank having its under surface formed of an outer section having substantially horizontal transverse elements and an inner section having its transverse elements curved upwardly and extended to form the elements of the 40 inner side of the last upper, and a substantially flat forepart, the rear portion of said forepart having a substantially concaved surface terminating in the outer and inner sections of the shank member whereby a 45 shoe formed on said last will support the 50 longitudinal and transverse foot arches.

In testimony whereof, I have signed my name to this specification.

CHARLES H. BROWN.
